STOKER.

Application filed September 28, 1926. Serial No. 138,250.

This invention is a continuation in part of our application Serial No. 33,414 filed May 28, 1925.

Our invention relates to progressive feed stokers, and has for its object the provision of apparatus of the character designated which shall be simple in design and operation and which shall be capable of effecting economical combustion of fuel and efficient disposal of refuse.

More specifically, the object of our invention is to provide an improved progressive feed stoker, together with means for operating said stoker whereby it exerts a continuous breaking and moving effect on the fuel being burned.

Apparatus embodying features of our invention is illustrated in the accompanying drawings forming a part of this application 20 wherein,

Fig. 1 is a perspective view looking downwardly on the stoker, some of the features thereof being omitted.

Fig. 2 is a transverse sectional view of the 25 stoker taken along the line II—II of Figure 1;

Fig. 3 is a perspective view of a series of grate members removed from the stoker;

Fig. 4 is a perspective view of a dump 30 grate member removed from the stoker;

Fig. 5 is a plan view of the driving mechanism for the stoker;

Fig. 6 is a fragmentary sectional view taken along the line VI—VI of Figure 1;

Fig. 7 is a sectional elevation showing one of the operating mechanisms for the ash disposal means of the stoker; and,

Fig. 8 is a view similar to Fig. 2 showing a modified form of our invention.

According to one embodiment of our invention, we provide a stoker having a retort located centrally thereof, and an overfeed grate section extending laterally of the retort and receiving fuel therefrom.

The overfeed grate section embodies a plurality of series of relatively narrow grate members hinged together in end-to-end relation and pivoted to the side of the retort. Each of the grate members is provided with lateral recesses for the passage of air to the fuel above the grate and with fluted lower body portions for cooling purposes. Means

are provided for raising and lowering the section at an intermediate hinged point thereof so that a motion is imparted to the section as a whole, such that the fuel supporting portion of each element of the grate section has a combined motion, one component of which is in the direction of the fuel supporting surface while the other component is at an angle to such surface. The last members of the section, considered in the direction of fuel feed, are adapted to slide upon a stationary support, thus effecting a reciprocatory feeding action of the section, pushing the refuse of the fuel on to the ash disposal mechanism. Air under pressure is provided beneath the grate section and the grate members are held closely together in side-by-side relation so that sifting of ashes through the grate section is prevented, while an ample supply of air for the combustion of fuel passes freely through the lateral recesses in the grates to the fuel bed. We thus provide a stoker which is easy to construct and assemble, which permits of ready removal and replacement of parts, and which is, at the same time, rugged and durable.

Referring now to the drawings for a better understanding of our invention, particularly to Figs. 1 to 4, inclusive, we show a stoker having a retort 10, supplied with fuel from a hopper 11, through the agency of an engine 12, driving a feeding ram 13. If so desired, one or more auxiliary feeding rams 14 may be provided in the retort.

Disposed on the two sides of the retort 10 are overfeed grate sections 16—16. Each of the overfeed grate sections 16 extends at substantially right angles to the retort 10 and receives fuel therefrom. After passing over the grate sections 16, refuse is discharged therefrom onto the ash disposal mechanism, illustrated as dump grates 17—17. The dump grates 17 each comprise a plurality of grate members 20 as shown in Fig. 4 and arranged in side-by-side relation to be more particularly described hereinafter.

Surrounding the stoker are a front wall 18, a rear wall 19 and slide walls 21 and 22. The stoker structure is supported centrally by a pair of channel beams 23 and 24 to which the retort 10 is suitably secured and by a pair of I beams 26 and 27. The channel beams 23 and

24 and the I beams 26 and 27 may be supported by the end walls of the furnace. Beneath the I beams 26 and 27 are suitable walls 28 and 29. Air is admitted beneath the structure by means of a conduit 31 so that the space beneath the stoker and between the walls 28 and 29 defines an air box.

Each of the overfeed grate sections 16 comprises a plurality of series of grate members, 10 each series herein shown as consisting of four members 36, 37, 38 and 39. All of the members 36 are pivoted to the sides of the retort at the upper edges thereof by means of a slot and cylinder connection 41. The members 37 are 15 hinged to the members 36 in groups of a suitable number of members by means of pins 42. The members 38 are likewise hinged to the members 37 by pins 43 and the members 39 are hinged to the members 38 by pins 44. 20 Each of the members 36 is somewhat L-shaped so that when assembled in the stoker, an upstanding leg 35 borders the retort 10 and forms in effect a portion of the side wall thereof. Another leg 34 extends at an angle 25 to the leg 35. The legs 34 are in effect that portion of the members 36 which, in conjunction with the members 37, 38, and 39, form the overfeed grate sections 16, 16. The form thus given the members 36 has an important 30 bearing on the fuel feed of the stoker as will appear more particularly hereinafter.

In Fig. 2, the members 37 are shown as being provided with depending cylindrically shaped lugs 46 for engagement by an operating link 47 driven by a crank arm 48 from a shaft 49. Inasmuch as all of the members 36 and 37 are held together by means of the hinge pins 42, it is only necessary that a sufficient 35 number of members 37, such as is shown in Fig. 2, be provided with lugs 46 in order to insure operation of the grate section. For example, in Fig. 3, I show the grate member 37' adjacent the grate member 36 as having no depending lug. The majority of the grate 40 members hinged to the grate members 36 are made in this manner.

All of the grate members are provided with lateral recesses 40 for the admission of air to the fuel being burned. The lower portion of 45 each of the grate members is narrower in cross section than the upper portion and is provided with ribs or fluted portions 45 which serve to cool the grates and also to preheat the air, in a measure, which is being admitted to the fuel. As may be seen from the drawing, the grate members 36 are provided with a greater number of recesses 40 per unit of length than the members 37, the members 37 a greater number than the members 38, and 50 the members 38 a greater number than the members 39. This arrangement of lateral recesses provides for the admission of air to the fuel bed moving over the grate section in proportion to the combustible in the fuel. 55 Where the fuel bed, adjacent the retort 10, is

comparatively fresh a liberal amount of air is supplied thereto, while remote from the retort the supply of air grows less and less as the combustible in the fuel diminishes. We thus provide for the most efficient burning of the fuel. Air for the combustion of gases driven off from the fuel in the retort 10 is supplied from an auxiliary air box 60 which may have air conveyed thereto through a conduit 65.

The shafts 49 are supported by a suitable 75 number of frame members 51, which extend transversely of the stoker and are secured to the channel beams 23 and 24 and to the I beams 26 and 27. The shafts 49 extend longitudinally of the stoker, the full length thereof 80 and are mounted to rock in their respective supports so that, when oscillated, they effect a raising and lowering of the grate sections at the hinged points 42 and cause the grate members 36 to be oscillated about their connections 41 with the retort 10.

Upon oscillation of the grate members 36 about the connections 41, it will be seen that the upstanding portions 35 will move toward and away from the retort. As the retort is 90 constantly being filled with fuel by the rams 13 and 14, such a movement of the upstanding portions 35 serves to aid in the transfer of fuel from the retort 10 to the legs 34 of the members 36.

The outer end of each of the grate sections, considered in the direction of fuel feed, is supported by a member 56 upon which the grate members 39 are slidable. The frame members 56 are hollowed out in cross sections 100 so that, as the grate members 39 slide back and forth thereover an oscillatory motion is imparted to them. In order that air may pass to the fuel above the grate members 39, suitable air ports 57 are provided in the frame members 56.

Intermediate the hinged connection 42, and the hinged connection 44 of each of the grate sections is interposed a tilting support 58 having an arcuate upper surface which engages the under surface of the member 37. When the hinged connections 42 are raised and lowered, oscillating the grate members 36 about their pivot points it will be seen that a reciprocating motion is imparted to the members 37, 38 and 39. The members 39 slide back and forth as previously described, over the members 56. The tilting supports 58, in supporting the intermediate parts of the grate section, tilt back and forth with the reciprocating motion and impose upon the sections above them a slight oscillatory movement. As stated, an oscillatory movement is imparted to the members 36 by the crank arm 48 and the link 47; however, so far as the motion of each overfeed portion 34 with respect to the overfeed fuel supporting surface is concerned, it may be regarded as compound, that is, with respect to such surface each portion 34 has motion in the general direction of such sur- 110 115 120 125 130

face and at an angle thereto. The combined oscillatory and reciprocatory movement of the remaining members 37, 38 and 39 of each of the grate sections 16, which was described 5 above, can also be considered as a compound motion having the same characteristics as that imparted to the portion 34 of the member 36. It may therefore be stated that a compound motion having the above mentioned 10 characteristics is imparted to the fuel supporting portions of each of the grate sections 16. The motion thus imparted to the grate sections serves to break up the fuel bed passing thereover and to progressively push 15 it onto the dump grates 17.

In considering more specifically the operation of the grate section 16, it is noted that each of the grate sections 16 are so constructed and arranged that an upward movement of 20 the hinge connections 42 causes the hinge connections 44 to also move upwardly; but during this movement the hinge connections 43 will move downwardly. Likewise, as the connections 42 and 44 move downwardly the connections 43 will move upwardly. Therefore, as either of the hinge connections 42, 25 43, or 44 moves in either direction, its adjacent hinge connections will move in an opposite direction. In other words, successive 30 joints of the grate sections 16 are moved in opposite directions with respect to the fuel supporting surface. The result of the peculiar motions of the connections is that the fuel bed will be raised and lowered at the hinge connections, thus serving to agitate the fuel bed and provide for an effective combustion of fuel and in addition provides an effective means for advancing the fuel toward the dump grates.

40 As stated above, each of the overfeed grate sections 16 provides a fuel supporting surface which is inclined downwardly in the general direction of fuel feed, that is, from the retort to the dump grate 17. The degree of the angular component of the combined movement which the fuel supporting portions of the members 36, 37, 38 and 39 have with respect to the fuel supporting surface, or rather the degree of motion with 45 respect to the fuel supporting surface which is imparted to the pivotal connections 42, 43 and 44, varies with the fuel feed; that is to say, the maximum amount of movement with respect to the fuel supporting surface takes place at the pivot connection 42, a lesser amount at the connection 43 and the least at the connection 44. This difference of movement between the connections 42 and 50 43 is caused by the design of the members 37 with respect to the members 36 and 38 and also by the positioning of the tilting supports 58 with respect to the hinged connections 43. In the present construction, the members 37 are shorter than their respective 55 members 36 and much shorter than their

respective members 38, and the tilting supports 58 are arranged in close proximity to the hinged connections 43. The result of such an arrangement is that the connections 42 will move below the general direction of the fuel 70 supporting surface for a greater distance than the hinge connections 43, and the connections 42 will move above the general direction of the fuel supporting surface a greater distance than the connections 43. A 75 greater degree of movement of the connections 42 could be effected by increasing the length of the members 37 and placing the supports 58 further away from the connections 42. It is noted that the degree of angular 80 movement of the members 39 is small when compared with any one of the remaining members by reason of the design of the support 57. The reason for this variation of movement between the succeeding pivotal 85 connections is that a more thorough agitation of the fuel bed is required at points nearest the retort so as to break up the coke when first formed, and permit the air for combustion to reach the burning fuel. This requirement, however, becomes less as the burning fuel approaches the dump grate.

The dump grates 17 are supported by shafts 61 which are suitably journaled in supports 62 secured to the I beams 26 and 27, 90 respectively. Each of the dump grate members 20 is provided with a squared hook portion 63 fitting over similarly formed squared portions 64 of the shafts 61. The dump grates 17 are adapted to be actuated in a 100 manner to be described more particularly hereinafter.

At the rear of the stoker and abutting the grate sections 16, is an angle member 66 bearing against the grate sections. Referring to Fig. 6, it will be seen that the angle member 66 is supported in a recess 67 of the rear wall 19 of the stoker. Bearing against the angle member 66 is a bell crank lever 68 having suspended from one of its arms a suitable 110 weight 69. The weight 69 serves to constrain the series of grate members in abutting side-by-side relation so as to prevent the sifting of coal and ashes between the grates.

Referring now to Fig. 5, we show the drive 115 mechanism for our improved stoker. The mechanism employed is in all essential respects similar to that disclosed in the application of Charles F. Miller, Serial No. 631,661, filed April 12, 1923 and assigned to the Westinghouse Elec. & Mfg. Company. The description of this mechanism will therefore be 120 briefly given.

In Figure 5, 71 represents the stoker engine cylinder and 72 the valve gear mechanism which is arranged to provide reciprocating motion of the piston within the cylinder. At 73, we show the piston rod which is connected at 74 to the fuel feeding ram 13. The piston rod 73 carries a clamp 130

76 having pivoted thereto a lever 77. The lever 77 is pivoted at its opposite end, to a link 78 which is also pivoted to a shaft 79. Journaled on the shaft 79 is a segmental 5 miter gear 81, which meshes with a similar gear 82 carried by the shaft 49. The gear 81 has an operating arm 83 which is connected by means of a link 84, with a fulcrum pin 86 which is movable within a curved slot 10 87 provided in the lever 77.

The position of the pin 86 within the slot 87 can be varied by means of a screw 88 operatively connected to the pin 86 and extending lengthwise of the slot and through 15 the opposite end of the lever 77. A hand wheel 89 serves to turn the screw 88 and thus move the pin 86 in the slot 87 when desired.

As the piston rod 73 reciprocates back and 20 forth it will be seen that an oscillatory motion is transmitted to the gear 81 through the lever 77, the link 84 and the arm 83, the lever 77 oscillating about its connections with the link 78. The motion transmitted 25 to the gear 81 is transmitted to the shaft 49 through the gear 82, and the shaft 49 serves to oscillate the members 36 in a manner already described. Inasmuch as the shaft 49 extends the full length of the stoker and is 30 operatively connected to all the members 36, the members 36 are all oscillated in unison. The members 37, 38 and 39 of each series also have imparted to them a reciprocatory motion in unison by the oscillation of the 35 members 36, while the tilting supports 58 cause a slight oscillatory motion to be imparted to the members 37 and 38.

Should it be desired to vary the amount 40 of movement of a grate section, the pin 86 can be moved within the slot 87 so as to vary the distance between the outer pivoted point of the lever 77 and the fulcrum pin 86. Motion thus transmitted may be readily varied from practically zero to whatever desired within the 45 limits determined by the length of the slot 87 and the travel of the engine piston.

It will be observed that the motion thus imparted to the overfeed grate section is coincident with the motion imparted to the 50 fuel feeding ram of the stoker. This feature is important in that it permits us to adapt movements of the overfeed grate section so that the stoker may evenly burn different grades or types of fuel.

55 The dump grate 17 may be operated in any suitable manner. We have illustrated in Fig. 7 a very satisfactory arrangement which we employ for that purpose. Secured to the shaft 61 of the dump grate 17, is an operating arm 91. The arm 91 is operated by means of a link 92 pivoted within a piston 93 which operates within a cylinder 94. Leading to the cylinder 94 is a pipe 96, which serves to admit fluid under pressure to move the piston 93 outwardly and turn the shaft 61, rais-

ing the dump grate 17. When the dump grate 17 is in its raised position, a catch 97 is arranged to engage the operating arm 91 to hold the dump grate in raised position and pressure in the cylinder 94 may be relieved 70 by means of a pipe 98 and valve 99. Whenever it is desired to lower the dump grate 17, the catch 97 is disengaged and the dump grate lowers itself by gravity. Fluid under pressure may then be admitted to the cylinder 94 75 through the pipe 96 to raise the dump grate, whereupon it may again be fixed in position by means of the catch 97.

Referring now to Fig. 8, we show a modified form of our invention which is similar in all 80 respects to that previously shown except as to the method of imparting the combined oscillatory and reciprocatory motion to the overfeed grate sections. In accordance with this modification we show grate members 85 101, 102, 103 and 104 hinged together, as previously described for the members 36, 37, 38 and 39, with the grate member 101 pivoted to the side of the retort 10 as previously described for the grate member 36. The grate member 104 is slidingly supported at its outer end on a stationary support 106. The end of the member 104 nearest the retort 10 is provided with a depending lug 107 connected through a link 108 with a stationary support 90 109. The grate member 102 has two depending lugs 111 and 112. The lugs 111 and 112 are connected by means of links 113 and 114 with a rocking lever 116 secured to the 95 shaft 49.

It will be seen that when the shaft 49 oscillates, its motion is transmitted to the grate section through the links 113 and 114, oscillating the grate members 101, 102 and 103, and the grate member 104 slides back and forth on the support 106. The link 108 serves also to impart an oscillatory motion to the grate member 104 during reciprocation. By this motion the fuel bed is continuously broken up and urged toward the dump 100 grate 17.

From the foregoing description, the operation of our improved stoker will be readily apparent. Fuel from the hopper 11 is supplied to the retort 10 by means of the ram 13 and auxiliary rams 14 on to the overfeed grate sections 16. At the same time, the overfeed grate sections 16 have imparted to them a compound motion, one component of which is in the general direction of the inclination of the grate section and another at an angle thereto, by means of the link and lever mechanism described so that the fuel is being constantly broken up and urged toward the ash disposal mechanism 17.

120 The amount of motion necessary to burn the particular fuel is regulated by positioning the fulcrum pin 86 within the slot 87 so that all of the combustible in the fuel will have been consumed by the time it reaches the ash 125 disposal mechanism 17.

disposal mechanism 17. Air for burning the fuel is supplied through the lateral recesses 40 of the grate members. The air in passing over the fluted portions 45 of the grate members cools them and, in a measure, is pre-heated. Gases driven off from the fuel in the retort 10 are consumed with the admixture of air supplied from the auxiliary air box 60. At intervals, when needed, the dump grate 17 may be lowered and the ashes thereon disposed of in any desired manner.

It is to be observed, that while we have shown and described our improved overfeed grate section as applied to the upper lateral edge of a horizontally arranged retort, that our invention is not limited to that particular application; for in so far as certain aspects of the invention are concerned, it might equally as well be applied to any stoker in which an overfeed grate is utilized for supporting the fuel during combustion.

From the foregoing, it will be apparent that we have devised an improved stoker which is rugged and durable, which is simple in construction and operation and which is capable of continuous operation over long periods of time, effecting an efficient burning of fuel thereon.

While we have shown our invention in two forms, it will be obvious to those skilled in the art that it is not so limited, but is susceptible of various other changes and modifications, without departing from the spirit thereof, and we desire, therefore, that only such limitations shall be placed thereupon as are imposed by the prior art or as are specifically set forth in the appended claims.

What we claim is:—

1. In a progressive feed stoker, a series of grate members pivotally connected together in end-to-end relation and extending in the direction of fuel feed, a stationary pivotal connection for the first member of the series considered in the direction of fuel feed, a stationary support for the last member of the series considered in the direction of fuel feed, said last member being slidable on said stationary support, and means for oscillating said first member about its stationary pivotal connection.
2. In a progressive feed stoker, a series of grate members pivotally connected together in end-to-end relation and extending in the direction of fuel feed, a stationary pivotal connection for the first member of the series considered in the direction of fuel feed, a support for the last member of the series considered in the direction of fuel feed, said last member being reciprocable on said support, a tilting support interposed at an intermediate point in the series, and means for raising and lowering a member of the series at one of the intermediate pivotal connections thereof.
3. In a stoker, a progressive feed fuel sup-
- porting structure comprising a plurality of series of articulated grate members disposed in parallel relation in the direction of fuel feed, a stationary member, a pivotal connection between the first member of each of the series considered in the direction of fuel feed and the stationary member, means for reciprocably supporting the last member of each of the series considered in the direction of fuel feed, a tilting support at an intermediate point of each of the series, and means for raising and lowering a member of each of the series at an intermediate hinged point thereof.
4. In a progressive feed stoker, a retort, a ram in the retort, a progressive feed fuel supporting structure extending laterally and sloping downwardly from the retort, said structure comprising a plurality of series of articulated grate members disposed in parallel relation in the direction of fuel feed, the first member of each of the series considered in the direction of fuel feed being pivotally connected to the upper edge of the retort, means for supporting the last member of each of the series for movement bodily toward and away from the retort, a tilting support interposed at an intermediate point of each of the series, and means for raising and lowering an intermediate hinged connection of each of the series.
5. In a progressive feed stoker, a retort, a ram in the retort, a progressive feed fuel supporting structure extending laterally and sloping downwardly from the retort, said structure comprising a plurality of series of articulated grate members disposed in parallel relation in the direction of fuel feed, the first member of each of the series considered in the direction of fuel feed being pivotally connected to the upper edge of the retort, means for raising and lowering the end away from the retort of the first member of each of the series, means for supporting for reciprocatory motion the last member of each of the series, said means being adapted to impart an oscillatory motion to said member in reciprocating and a tilting support between said last-mentioned support and said raising and lowering means.
6. In a stoker, the combination with a retort having a fuel feeding ram, of an articulated grate section pivotally supported adjacent the side of the retort, means for raising and lowering an intermediate portion of the section at one of its points of articulation and a stationary support for the section at its portion most remote from the retort, said portion being adapted to slide on said stationary support, said stationary support being hollowed out in cross section so as to impart an oscillatory motion to the portion sliding thereover.
7. In a stoker, the combination with a retort having a fuel feeding ram, of an articu-

- lated grate section pivotally supported adjacent the side of the retort and extending laterally therefrom, means for imparting an oscillatory motion to the portion of the section adjacent the retort, and means for slidably supporting the section at a portion thereof remote from the oscillating portion, the last named supporting means being adapted to impart an oscillatory motion to the portion in sliding thereover.
8. A stoker comprising a retort, a ram for feeding fuel into said retort, and a fuel supporting structure extending laterally from the retort, characterized by that the fuel supporting structure comprises a plurality of series of grate members disposed in parallel relation with the members of each series pivotally connected together in end-to-end relation, means for raising and lowering a member of each of the series of members at an intermediate point of the series, and means for slidably supporting each of the series of members at its end remote from the retort.
9. In a stoker, the combination of a retort, a ram in the retort, means for driving the ram, a progressive feed fuel supporting structure disposed at substantially right angles to the retort and comprising a plurality of parallel series of grate members pivotally connected together in end-to-end relation, the first member of each series considered in the direction of fuel feed being pivotally supported adjacent the upper edge of the retort, means for supporting the last member of each of the series for movement bodily toward and away from the retort, a rocking shaft, an operative connection between said shaft and said first member of the series for oscillating said member about its pivotal support adjacent the retort, link and lever mechanism connecting the means for driving the ram and the shaft for imparting motion to the shaft simultaneously with the motion of the ram, said last-mentioned mechanism including a lever and means for varying the effective movement of the lever to vary the range of oscillation of the shaft.
10. In a stoker, a retort, a ram in the retort, a progressive feed overfeed grate section pivotally support adjacent a side of the retort and receiving fuel therefrom, said grate section comprising a plurality of series of relatively narrow grate members having lateral recesses providing tuyère openings, the members of each series being pivotally connected together in end-to-end relation, means for raising and lowering a portion of each of the sections at an intermediate pivotally connected point thereof, an air box beneath the section, and yielding means for constraining the series of the section in abutting side-by-side relation.
11. In a progressive feed stoker, an overfeed grate section comprising a plurality of series of grate members, the members of each series being pivotally connected together in end-to-end relation and the respective series being disposed in abutting substantially parallel relation, a pivotal support for the first member of each of the series considered in the direction of fuel feed, means for oscillating all of the first members in unison about their pivotal supports and imparting a reciprocating motion to all the other members in unison, and means for supporting the reciprocating members whereby a slight oscillatory movement is imparted to all in unison during reciprocation.
12. In a stoker, the combination of a retort, a grate section providing an overfeed fuel supporting surface arranged to receive fuel from the retort and including a series of members pivotally connected together in end-to-end relation, said grate being pivotally secured at the end located adjacent the retort, means for supporting the end remote from the retort for movement bodily toward and away from the retort, and means for moving successive pivotal connections of the grate in opposite directions with respect to the fuel supporting surface.
13. In a stoker, the combination of a retort, a grate section providing an overfeed fuel supporting surface arranged to receive fuel from the retort and including a series of members, means for pivotally connecting the members together in end-to-end relation, means for pivotally supporting the end of the grate disposed adjacent the retort, means for supporting the end of the grate remote from the retort for movement bodily toward and away from the retort, a rocker bearing for supporting an intermediate one of the grate members, and means for imparting a raising and lowering action to an end portion of the grate member supported by the rocker bearing, so as to cause successive pivotal connections of the grate to move in opposite directions with respect to the fuel supporting surface.
14. In a stoker, the combination of a retort, ash disposal mechanism spaced from the retort and extending substantially parallel to and at a lower elevation than the retort, a series of articulated members extending laterally and downwardly from the retort to the ash disposal mechanism to provide an overfeed grate section having a downwardly inclined fuel supporting surface, means adjacent the retort for pivotally supporting one end of the grate section, means adjacent the ash disposal mechanism for supporting the other end of the grate section for movement bodily toward and away from the retort, and means providing for the simultaneous movement of the members of the grate section, such that the fuel supporting portion of each member has a component of motion.

ion in the general direction of the fuel supporting surface and a component of motion at an angle to such surface.

15. In a stoker, the combination of a retort, an ash disposal mechanism spaced from the retort and extending substantially parallel to and at a lower elevation than the retort; a series of articulated members extending laterally and downwardly from the retort to the ash disposal mechanism to provide an overfeed grate section having a downwardly inclined fuel supporting surface, means adjacent the retort for pivotally supporting one end of the grate section, means adjacent the ash disposal mechanism for supporting the other end of the grate section for movement bodily toward and away from the retort, and means for moving the grate section at successive points of articulation in opposite directions with respect to the fuel supporting surface.

16. In a progressive feed stoker, the combination of an overfeed grate section providing a downwardly inclined fuel supporting surface adapted to receive fuel at the upper end thereof, the grate section comprising a plurality of series of grate members, the members of each series being pivotally connected together in end-to-end relation and the respective series being disposed in substantially parallel relation, means providing for movement of the members of the grate section such that the fuel supporting portion of each member has a component of motion in the general direction of the fuel supporting surface and a component of motion at an angle to such surface, and means for supplying air through the grate section in diminishing quantities considered in the direction of fuel feed.

17. In a progressive feed stoker, the combination of an overfeed grate section providing a downwardly inclined fuel supporting surface adapted to receive fuel at the upper end thereof, the grate section comprising a plurality of series of grate members, the members of each series being pivotally connected together in end-to-end relation and the respective series being disposed in abutting substantially parallel relation, all of the members being provided with lateral recesses forming tuyère openings, the number of said tuyère openings per unit of length along a series diminishing in the direction of fuel feed, means for supplying fuel to the section, and means providing for movement of the members of the grate section such that the fuel supporting portion of each member has a component of motion in the general direction of the fuel supporting surface and a component of motion at an angle to such surface.

18. In a stoker, the combination of an overfeed grate section providing a fuel supporting surface and including a series of grate

members pivotally connected together in end-to-end relations; means providing for the feeding of fuel to one end of said grate section; means for supporting the first grate member of said series considered in the direction of fuel feed; means for supporting the remaining members of said series for bodily movement in a direction towards and away from the fuel receiving end of said grate section; and means for moving the entire grate section; the grate section, the supporting means and the moving means being so constructed and arranged that the fuel supporting portion of each grate member has a component of motion in a direction away from the fuel receiving end, and a component of motion at an angle to the plane of the fuel supporting surface.

19. In a stoker, the combination of a grate section providing a downwardly inclined fuel supporting surface and including a series of grate members pivotally connected together in end-to-end relation; means providing for the feeding of fuel to the upper end of said grate section; means for supporting the first grate member of said series considered in the direction of fuel feed; means for supporting the remaining members of said series for bodily movement in a direction toward and away from the fuel receiving end of said grate section; the grate section, the supporting means and the moving means being so constructed and arranged that the fuel supporting portion of each grate member has a component of motion in a direction away from the fuel receiving end, and a component of motion at an angle to the general plane of the fuel supporting surface.

20. In a stoker, the combination of an overfeed grate section providing a fuel supporting surface and including a series of grate members pivotally connected together in end-to-end relation; means providing for the feeding of fuel to one end of said grate section; means providing a pivotal support for the first grate member of said series considered in a direction of fuel feed; means for supporting the remaining members of said series for bodily movement in a direction toward and away from the fuel receiving end of said grate section; and means for oscillating the first member of said series about its pivotal support.

21. In a stoker, the combination of a grate section providing a fuel supporting surface and including a series of members pivotally connected together in end-to-end relations; means providing for the feeding of fuel to one end of the grate section; means for supporting the first grate member of said series considered in the direction of fuel feed; and means for supporting the remaining grate members of said series for bodily movement in a direction toward and away from the fuel receiving end; and means for moving the

members such that the fuel supporting portion of each member has a component of motion in the general direction of the fuel supporting surface and another component at an angle to said surface; the said grate section and its moving and supporting means being so constructed and arranged that considered in the direction of fuel feed, the degree of angular movement of one member of ²⁰ the series is greater than the next succeeding member of the series.

22. In a stoker, the combination of a grate section providing a fuel supporting surface and including a series of members pivotally connected together in end-to-end relation; means providing for the feeding of fuel to ²⁵

one end of the grate section; and means for moving successive pivotal connections in opposite directions respectively to the fuel supporting surface; the said grate section and its moving means being so constructed and arranged that the degree of movement with respect to the fuel supporting surface imparted to successive pivotal connections when considered in directions of fuel feed, decreases from the first pivotal connection toward the last.

In testimony whereof, we have hereunto subscribed our names this 24th day of Sept., 1926.

ROBERT A. FORESMAN.
JOHN E. LARRABEE.
